STORAGE RACK

Clark H. Waycott, Sr., Sacramento, Calif.

Application May 4, 1942, Serial No. 441,690

1 Claim. (Cl. 211—81)

This invention relates to storage racks for a plurality of containers, such as five gallon oil cans, for instance, the cans being mounted in accessible rows in any number desired and in such a manner as to admit ready pouring of the contents or fluid being stored without removing the individual container from the rack or battery of containers.

A further object of the invention is the provision of a storage pouring rack especially serviceable in dispensing stations utilized by automobile owners and the like and whereby any small desired quantity of the fluid so stored may be removed at will easily and quickly without necessity of manually lifting the container and with the entire rack filled with containers in a neat and compact manner serviceable within a small sized closet or at any convenient point within a salesroom or office.

With these and other objects in view that will be better understood as the nature of the invention is described herein in connection with the accompanying drawing, in which,

Figure 1 is a front elevation of my pouring storage rack in its normal empty arrangement;

Figure 2 is a side elevation thereof with one can or container, indicated by dotted lines, in its normal idle position;

Figure 3 is a horizontal transverse sectional view through the rack with one container, shown by dotted lines;

Figure 4 is a fragmentary vertical sectional view taken through one of the individual holders or hangers of the containers being stored; and

Figure 5 is a fragmentary sectional view upon an enlarged scale showing one of the adjustable trunnion means for the holding frame of a single fluid storage container.

The extensive use is now well known of providing such fluids and oils, disinfectants, liquid soaps and the like in large containers or cans such as those holding a number of gallons and which by reason of the considerable weight of each unit or container, renders the storing for immediate easy service use of any individual container a more or less difficult and arduous undertaking.

This is obviated and overcome by my invention preferably employing for convenience a plurality of racks, each consisting of a battery for trunnioning for use a plurality of more or less bulky and heavy containers. Such a rack for a battery of three containers is shown in Figs. 1 and 2 of the drawing and designated 6 with a single substantially cubical can or container, des-

ignated by dotted lines, 7, in its normal idle position.

The individual holder for a can 7 consists of the stirrup or saddle 8, substantially U-shaped with oppositely projecting trunnions or axles 9 for removable reception within conveniently positioned pairs of notches or slots 10, it being noted that substantially rectangular bands or hoops 11 surround the can 7 and so positioned by having inwardly directed overlapping portions or fingers 12 engaging the forward side of the can thereby preventing removal thereof accidentally or otherwise when tilted upon the axles 9.

For further retaining the cans 7 normally in upright position, an angle brace 13 may be secured by a set screw or bolt 14 with its upper turned end 15 adapted for hooking over the top of the can 7, as shown in Figs. 1, 2 and 3 of the drawing, and being for the purpose of preventing the can 7 from accidental falling from the rack during the operative tilting of said can 7.

The construction and operation of the invention will be understood from this detailed description thereof and with the rack 6 placed in any convenient point where the fluid dispensed is desired to be removed, a can 7 of any desired form, and herein illustrated as of the conventional substantially cubical form, is positioned in the frame consisting of the parts 3, 11, 12 and 13, as herein described, by lifting the can 7 and its frame 8—11 to position the axles 9 in opposite slots or notches 10, the readily tilting of the can 7 is accomplished for pouring the desired quantity of its contents such as lubricating oil, liquid soap or the like, out of the spout 16 when the can 7 may be again returned to its upright normal position. The hook member 13 may be provided with a slot 17 through which the securing bolt or screw 14 extends and whereby the hook end 15 is clamped against the top of the can 7, thereby preventing accidental removal or tilting of said fluid containing can 7.

It is apparent that the can 7, with its enclosing frame or carrier 11, 8, 13, may be readily lifted from the inwardly inclined trunnioning notches 10 of the rack 6 for positioning at any desired height where such notches are provided in the frame. A convenient hook 19 may be carried by the rack 6 for attaching in any convenient manner a plurality of such racks together for convenient use in battery formation positioned for instance against the wall of a building. The bottom 20 of the rack 6 may have a forward projection 21 if found desirable and upon which the moved can 7 may be readily rested. It is also

noted that any desired form of convenient lock or stop may be arranged for the can 7 to prevent loss by theft of these containers.

This arrangement not only affords a great convenience for the sellers of fluids in service stations and the like but in fact a considerable saving of fluids in the dispensing operation. While the form of the invention herein shown and described is believed to be the preferred embodiment thereof, it is to be understood that changes may be made in form, proportion or details of construction without departing from the spirit and scope of the invention as set forth in the appended claim.

I claim:

In a storage rack of the character described, a vertical frame structure adapted for the pivotal support of containers, said frame structure in-

cluding vertical corner posts, container supporting saddles pivotally mounted between the corner posts, each saddle including a vertical U-shaped strap, a horizontal strap having the side legs thereof secured intermediate their ends to the upper ends of the legs of the vertical strap, pivot pins at the points of connection of said straps for mounting on said corner posts, the spaced front ends of the horizontal side legs carrying inwardly directed extensions adapted to overlie a container supported in the saddle, and a container brace bar having its lower end supported on and vertically adjustable relative to the closed end of the horizontal U-shaped strap with its upper end angularly bent to overlie the upper end of a container.
